UNITED STATES PATENT OFFICE.

MATTHIAS BROCK, OF BOSTON, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

1,376,387.

Specification of Letters Patent. Patented Apr. 26, 1921.

Application filed May 6, 1918. Serial No. 232,917.

To all whom it may concern:

Be it known that I, MATTHIAS BROCK, a citizen of the United States, residing at Boston, in the county of Suffolk and State of 5 Massachusetts, have invented certain Improvements in Methods of Making Shoes, of which the following description, in connection with the accompanying drawings, is a specification, like reference characters on 10 the drawings indicating like parts in the several figures.

This invention relates to improvements in methods of making shoes and more particularly to methods of molding or shaping the 15 upper materials at an end of a shoe to prepare the shoe for sewing around the end. This improvement in shoe making methods is applicable to both the heel and toe ends of shoes and in accordance with the practice 20 herein exemplified is characterized by the molding of the upper materials, which may include the end stiffener, to a shoe form and over the marginal portion of the tread face of the form to produce a flange upstanding 25 at a definite angle relatively to the tread face of the form and located a predetermined distance inwardly from the edge of the tread face.

It is contemplated that in the practice 30 illustrated both the upper and end stiffener may be molded together to provide a multiply structure fitting the side faces of the shoe form, the plies reinforcing each other and extending inwardly over the tread face 35 of the form a predetermined distance from the edge and being molded together at their marginal portions to form a flange upstanding substantially perpendicularly to the tread face at a predetermined distance inwardly from its edge.

This molding operation may be preliminary to lasting and, in that event, greatly facilitates the subsequent lasting operation, or, with the cheaper grades of 45 shoes, it may entirely supersede the lasting operation, the molded upper with the end stiffener being stitched to the shoe sole by means of the molded flange which will form a sewing flange coöoperating with the sewing 50 rib of the sole. Certain classes of shoes

have what is known as "sewed heel seats," the upper at the heel seat being sewed, and not nailed as usual, to the heel end of the insole, and the outsole also where one is used being attached by stitching.

A conspicuous example of a shoe having a sewed heel seat is found in the so-called "powder mill" shoe which is sewed entirely around the heel end and is without an attached heel because of the danger of explosion from heel nails or pegs. To illustrate the practice of the method of this invention, therefore, I have selected this type of shoe as embodying structural requirements to which my improved method of shoe 60 making is particularly applicable. Shoes of this type must have permanence of shape, be cheaply manufactured and contain no tacks or nails in the heel seat. My improved method of shoe making, when practised in 65 the manufacture of shoes of this type, shapes the upper and end stiffeners to the required form, dispenses with the necessity of a subsequent lasting step and provides the upper with sewing flanges for stitching to the sewing 70 rib of the sole. This, as previously stated, is of particular advantage at the heel seat which is necessarily sewed and cannot be nailed, and accordingly, for the purpose 75 of illustrating the practice of the method, I have selected the heel end of a shoe of the "powder mill" type. It is to be understood, however, that the practice of the method is not necessarily limited to shoes of this type or to the heel ends of shoes.

In the appended illustrative drawings, Fig. 1 shows a "powder mill" shoe upper with the upper and heel stiffener stock molded to the desired form and provided with a molded upstanding sewing flange in 80 accordance with the method of this invention.

Fig. 2 is a vertical section on the line 2-2 of Fig. 1 and shows the molded and flanged heel seat end of the shoe.

Fig. 3 is a vertical section through a last having mounted on its tread face an insole having a sewing rib around its heel end to which the flanged and molded upper is to be stitched,

Fig. 4 is a view of the shoe upper as assembled on said last and sewed with a welt to the heel seat portion of the insole.

Fig. 5 is a view of a completed shoe having a sewed heel seat,

Fig. 6 shows in perspective portions of an apparatus which may be used to practice the method, and

Figs. 7, 8 and 9 illustrate successive steps of the method as practised by the use of the apparatus shown in Fig. 6.

In practising my improved method in the manner illustrated in connection with the heel ends of "powder mill" shoes, the upper and unmolded heel stiffener or counter are mounted upon a shoe form functioning as an inner mold and conforming to the shape of the rear end of the shoe, although preferably slightly exaggerated as to the side contours so as to "over mold" and allow for the reaction of the stock from the stretching and compressing action in molding. The stock, including the unmolded heel stiffener or counter, is then clamped and molded to the side faces of the shoe form by an outer mold of corresponding shape which is closed against the inner mold under substantial pressure. The upstanding portions of the upper stock including the heel stiffener are then molded inwardly over and down on the marginal tread face of the form by a rigid molding instrumentality, such as formed wiper plates, and the marginal portions of the stock at a predetermined distance from the edges of the form are molded together between said rigid wiper plates and the flange forming face of a second rigid molding member superposed in determinate position on the tread face of the form to produce a flange upstanding from the tread face at a definite angle determined by the angular relation of the side or flange forming face of said second molding member to the tread face of the form, this angle, preferably, producing a flange extending substantially perpendicularly to the tread face of the form or inner mold.

With the heavy stiff upper materials it may be necessary to repeat this molding operation a number of times to "set" the flange and to form a permanent clearly defined angle at the base of the flange. The operation is, therefore, repeated as often as is found necessary, and preferably in all cases a plurality of times so as closely and permanently to mold the upper and stiffener stock to the shape of the margin of the tread face of the form and of the flange forming side face of the second rigid molding instrumentality.

The molded upper and heel stiffener are then removed from the shoe form and the heel end of the shoe is ready to be sewed to the insole. With "powder mill" or other shoes, the toe portion of the upper and toe

stiffener may be similarly molded to a suitably shaped shoe form and the margin of the upper correspondingly shaped by suitable molding instrumentalities after which the upper and welt are stitched to the sewing rib of the insole which extends entirely around the shoe. The shoe is then subjected to the usual trimming and filling operations and an outsole is applied and stitched to the welt in the usual manner.

In the illustrative drawings, the molded heel end 2 of the shoe upper is shown as having a horizontal portion 4 molded with the heel stiffener or counter 8 over the heel seat face parallel with said face, the marginal portions of the upper stock being molded together to form a flange 6 extending around the heel seat. This flanged margin of the upper at the heel seat is stitched to the sewing rib 10 extending around the heel seat of an insole, such as 12, Fig. 3, mounted upon a last 14 to which the upper conforms and having the usual margin or feather 16 to which the horizontal portions 4 of the molded upper and counter conform, the upstanding flange 6 abutting the sewing rib 10 around the heel seat of the insole and, in the illustrated shoe, being stitched to the sewing rib of the insole together with a strip of welting 18 (Figs. 4 and 5), an outsole 20 (Fig. 5) being subsequently applied over the insole and stitched to the welt in the usual manner.

One form of apparatus by the use of which the method may be practised is shown and claimed in my copending application Serial No. 235,814 filed on May 21, 1918, and portions of such apparatus are herein illustrated in Figs. 6 to 9 inclusive, although it will be understood that the practice of the method is not dependent upon the use of apparatus of this or of any other specific form. As illustrated in Figs. 7 to 9, the end portion of the upper materials, including an unmolded heel stiffener, is clamped around a shoe end form 22 by the use of an outer clamp member or mold 24 into operative relation to which the form 22 is moved rearwardly from its idle position indicated in Fig. 6, the margin of the materials projecting beyond the bottom face 26 of the form a suitable distance to provide for the subsequent molding of the margin to produce the required inturned and upstanding flange portions. The form 22 supports on its bottom face a flange forming plate 28 provided with a rib which projects within a guide-way 30 in the form to guide the plate for movement lengthwise of the form. A stop screw 32 projecting into a slot 34 in the plate 28 determines positively the limit of forward movement of the plate, and by engagement with a set screw 36 which is threaded in the plate determines also adjustably the limit of backward movement of the plate.

The plate 28 is normally held at its limit of backward movement by means of a spring plunger 38 in engagement with one arm 40 of a bell crank lever the other arm 42 of which bears against the outer end of the screw 36.

The plate 28 has an outer edge contour similar to that of the edge of the bottom face of the form 22, although of smaller curvature, and normally the plate may be positioned, for example, as shown in Fig. 7 with the rear portion of its edge face substantially flush with the rear end face of the form. As thus positioned, the edge face of the plate engages the upstanding margin of the materials around the rear end of the form initially against the pressure of end embracing wiper plates, one of which is shown at 44, these plates being moved forwardly and closed in laterally of the form in any suitable manner, and their inner edges having a contour such as to press the margin of the upper firmly against the edge face of the plate 28 around its rear end and along its sides when the wipers are in closed position. By reference to Figs. 7, 8 and 9 it will be seen that as the wipers begin to close inwardly the plate 28 is pressed yieldingly forward along its guideway against the resistance of its controlling mechanism, thus pressing the upper materials closely against the edges of the wipers around the end of the form where the curvature of the materials is pronounced and where the margin must be gathered as it is wiped inwardly, the yielding plate thus contributing to smoothness and uniformity in the gathering and overwiping of the materials and assisting also in causing the materials to be held tightly and operated upon effectively by the wiper plates in their overwiping operation.

Before the entire width of the margin of the upper materials has been stripped from between the wipers and the inner plate 28 and wiped down on the bottom face of the form, further forward movement of the plate is stopped by the resistance of the screw 32 and the plate then serves as an unyielding abutment against which the portion of the margin of the materials still upstanding is pressed with increased molding pressure by the continued movement of the wiper plates, these plates serving finally to mold the margin of the materials against the edge face of the plate 28 along both sides as well as around the rear end and to form a sharp angle in the materials in conformity to the angle between the edge face of the plate and the bottom face of the form.

If desired, and in accordance with one aspect of the method, the overwiping operation may be repeated a plurality of times to produce a cumulative molding effect upon the margin of the upper, the wipers being preferably retracted only partially from

over the bottom face of the form and then again advanced. As this overwiping and molding operation is repeated, the inner plate 28 is preferably restrained from outward return movement under the impulse of the spring plunger 38 by means of a latch 46 which engages the end of the arm 40 to hold it upraised in the position to which it is moved by the first advance of the plate 28. Finally the wipers are backed entirely off, the upper is released from clamping pressure between the inner and outer forms, and upon release of the arm 40 by the latch 46 the plate 28 is returned to its initial position.

By the practice of the described method the heel end of a shoe upper and the unmolded counter may be molded to a form and provided with a flange upstanding at a definite angle with relation to the tread face of the form at the heel seat and located a predetermined distance inwardly from the edge of said face whereby the shoe upper so molded may be united to an insole with said flange stitched to a sewing rib extending around the heel seat to provide a sewed heel seat, as hereinbefore explained. As previously pointed out, this same method may also be practised in the molding of the toe of the shoe.

Having thus described my invention, what I claim as new and desire to secure by Letters Patent of the United States is:—

1. That improvement in methods of making shoes which consists in molding an upper and a heel stiffener together to produce a multi-ply structure fitting the side faces of a heel form, molding the marginal portions of the upper and stiffener together inwardly over the heel seat face of the form for a predetermined distance parallel with said face, and molding the said marginal portions together substantially perpendicularly to said face into an upstanding flange extending around the end of the heel seat.

2. That improvement in methods of preparing shoes to be sewed around the end which consists in molding an upper and an end stiffener together to produce a multi-ply structure fitting the lateral contour of a shoe end form and in which structure the plies of material molded together reinforce each other, molding the marginal portion of the materials together inwardly over the tread face of the form for a predetermined distance, and molding the said upper and stiffener together between unyielding molding instrumentalities into a sewing flange standing substantially perpendicularly to said tread face around the end of the form.

3. That improvement in methods of preparing shoes to be sewed around the end which consists in positioning the end portion of upper materials around a shoe form, and molding the margin of said materials

between and in contact with rigid molding instrumentalities to produce a flange upstanding at a definite angle with relation to the tread face of the form around the end of the form and located a predetermined distance inwardly from the edge of said tread face.

4. That improvement in methods of shaping shoe uppers which consists in positioning upper materials about a shoe form with the margin of the materials projecting beyond the bottom face of the form, clamping said projecting margin in upstanding relation to the bottom face of the form and carrying the margin thus clamped inwardly over said face while permitting it to slip and shaping a portion of it in parallel relation to said face, and then holding substantially stationary a portion of the margin still clamped in upstanding relation to the bottom face of the form and increasing the pressure against said upstanding portion to mold it in that relation to the form.

5. That improvement in methods of shaping shoe uppers which consists in positioning the end portion of upper materials around a shoe form with the margin of the materials projecting beyond the bottom face of the form, wiping the margin of said materials inwardly over the bottom face of the form, pressing against the inner surface of the margin of the materials as the wiping progresses to hold the unwiped portion upturned from the bottom face of the form, and before the entire width of the margin has been wiped down upon said face opposing substantially unyielding resistance against the inner surface of the portion still upturned and increasing the pressure against its outer surface to produce a molded flange extending at a pronounced angle to said face.

6. That improvement in methods of shaping shoe uppers which consists in clamping the end portion of upper materials around a shoe form with the margin of the materials projecting beyond the bottom face of the form, gathering and wiping the margin of said materials inwardly over the bottom face of the form around its end, applying yielding outward pressure against the inner surface of the margin of the materials continuously around the end of the form as the wiping progresses to cause the materials to be gathered substantially free from wrinkles and wiped smoothly down upon the bottom

face of the form, and before the entire width of the margin has been wiped down upon said face increasing the pressure against the inner and outer surfaces of the portion of the margin still upstanding while substantially preventing further wiping down of said upstanding portion to mold said portion into a flange projecting at an angle to the bottom face of the form.

7. That improvement in methods of shaping shoe uppers which consists in clamping the end portion of upper materials around a shoe form with the margin of the materials projecting beyond the bottom face of the form, wiping the margin of said materials inwardly over the bottom face of the form, pressing yieldingly outward against the inner surface of the margin of the materials around the end of the form as the wiping progresses to hold the unwiped portion upstanding from the bottom face of the form, before the entire width of the margin has been wiped down upon said face opposing substantially unyielding resistance against the inner surface of the portion of the margin still upstanding and increasing the pressure against its outer surface to produce a molded flange projecting at an angle to the bottom face of the form, and repeating the overwiping and pressure applying operation against the outer surface of the materials while continuing to oppose unyielding resistance against the inner surface of the upstanding portion of the materials.

8. That improvement in methods of shaping shoe uppers which consists in clamping the end portion of upper materials around a shoe form with the margin of the materials projecting beyond the bottom face of the form, gathering and wiping the projecting margin of the materials inwardly against the bottom face of the form around its end throughout a portion only of the width of said margin, and then opposing substantially unyielding resistance against the inner surface of the unwiped portion of the materials while holding said portion upturned and increasing the inward wiping pressure to mold the inner portion of the margin into a flange upstanding at a pronounced angle to the bottom face of the form.

In testimony whereof I have signed my name to this specification.

MATTHIAS BROCK.
